UNITED STATES PATENT OFFICE.

HENRY G. DIBELKA, OF CHICAGO, ILLINOIS, ASSIGNOR TO THE KINGSLEY-MILLER COMPANY, OF CHICAGO, ILLINOIS, A CORPORATION OF ILLINOIS.

DESIGN FOR A RADIATOR CAP.

Application filed October 5, 1928. Serial No. 28,375. Term of patent 7 years.

To all whom it may concern:

Be it known that I, HENRY G. DIBELKA, a citizen of the United States, residing at the city of Chicago, in the county of Cook and State of Illinois, have invented a new, original, and ornamental Design for Radiator Caps, of which the following is a specification, reference being had to the accompanying drawing, forming part thereof.

In this drawing:
Figure 1 is a top plan view of the radiator cap;

Figure 2 is a front elevation of the cap; and
Figure 3 is a side elevation of the cap.

I claim:

The ornamental design for a radiator cap, as shown.

HENRY G. DIBELKA.
